MAHLON E. LAYNE, OF HOUSTON, TEXAS.

WELL-BORING ROD.

1,266,831.

Specification of Letters Patent. Patented May 21, 1918.

Application filed February 5, 1917. Serial No. 146,581.

To all whom it may concern:

Be it known that I, MAHLON E. LAYNE, a citizen of the United States, residing at Houston, in Harris county, Texas, have invented certain new and useful Improvements in Well-Boring Rods, of which the following is a specification.

The invention relates to an improvement in well boring rods, or other similar devices in which a hollow rod or shaft is used as a rotary power transmission shaft. The invention has for its primary objects the provision of means for reinforcing or stiffening a well boring rod, so that a lighter tube may be used than would otherwise be the case; the provision of means whereby the whipping or lateral vibration of the rod is reduced and its life increased due to the stiffening means; and the provision of means especially desirable in large size relatively thin rods, such as can be used where inside couplings like those of my Patent No. 1,223,591, April 24, 1917, are employed. Certain embodiments of the invention are illustrated in the accompanying drawings, wherein—

Figure 1 is a longitudinal section through one embodiment of the invention; Fig. 2 is a longitudinal section illustrating certain modifications of the construction; Fig. 3 is an end view of the construction of Fig. 4; and Fig. 4 is a section through still another modification.

Referring to Fig. 1, the numeral 1 represents a well boring rod or tube provided at intervals with internal stiffening rings or portions 2, carrying at its ends the coupling members 3 and 4. The coupling members 3 and 4 are preferably of the type shown and claimed in my co-pending application, Serial Number 808,889, heretofore referred to, such members being rigidly secured in position in the ends of the tube by welding or shrinking or by any of the means shown in the said application.

The stiffening rings or thickened portions 2 are spaced apart at any desired interval and may be formed by any of the upsetting processes known in the arts or by rolling the metal in sheets with the raised portions thereon and subsequently forming such sheets into tubes.

Fig. 2 illustrates two modifications of the invention wherein the tube or rod 5 is provided with the stiffening rings 6, 6^a, 6^b, which are not integral with the tube. They

may be forced into position by sufficient power to insure a tight fit, or may be secured by shrinking, the rings being placed cold in a heated tube, or they may be positioned and held in place by means of lugs 6^c formed on the inside of the tube. The securing of the rings is also preferably made more positive by spot welding or by using some mechanical means for attaching them to the walls of the pipe, there being a wide variety of means which might be employed for this purpose. It is also possible to secure the rings by placing them in position and subsequently expanding them.

Figs. 3 and 4 illustrate another method of insuring maintenance of the rings 7 in proper position in the tube 8. These rings are provided with grooves 9 (Fig. 3) along one side through which the holding rod 10 extends, such holding rod being provided with upset portions 11 on opposite sides of each ring. The rings are preferably tightly fitted into position and the rod 10 is depended upon to insure their proper maintenance in position even though they should become loosened by the vibration or for any other reason.

The foregoing is merely illustrative of the invention, as it will be seen that a large number of other means well known in the mechanical arts might be employed for positioning and securing the rings and that a variety of methods and machines might be employed for either forming the rings 90 integral with the pipe or for positioning and securing them. In each case the rings whether integral with the pipe, or fitting tightly therein, or somewhat loosely, perform the same function of stiffening the tube. A tube when subject to torsional strain, tends to fail by twisting into a smaller diameter or collapsing, and the rings or thickened portions resist this collapsing action. By a proper use of the rings 100 it is possible to use a lighter tube than would otherwise be possible, and a tube of the same thickness thus reinforced is much stronger than a tube without the reinforcing portions. The tube is also much less 105 subject to whipping or lateral vibration so that the life of the tube is prolonged by the use of the stiffening rings which reduce the weakening incident to the constant lateral vibration and twisting torsion.

The construction is particularly useful where couplings of the type shown in Fig.

1 are used, although any ordinary pipe coupling means may be used, such for example, as that shown in Fig. 2, where the ends of the tube are threaded and screwed into the 5 coupling 12. The couplings in Fig. 1 are inside couplings with no portion thereof projecting outside the outer diameter of the tube, so that a larger tube can be used as a boring rod in a well casing of a given 10 diameter than would be the case if couplings were used of the ordinary type involving enlargements at intervals throughout the length of the boring rod. A relatively larger tube of this type and having 15 a relatively thin wall, in order that the weight and expense may not be too great, practically requires increased strength such as is afforded by any one of my various forms of reinforcing rings. It will 20 also be seen that with this type of coupling as shown at 3 and 4 of Fig. 1, the tube is completely reinforced, the couplings constituting stiffening rings or members at the extreme ends of the tube, while the rings

2 provide the necessary stiffness intermediate the ends. A tube section is thus provided of uniform stiffness from end to end and there is no weak spot tending to yield when the twisting strain is excessive. Furthermore, it is to be noted that the reinforcing rings have the effect of distributing the torsional strains over the entire length of a section of the rod, that is to say, while in the aggregate the amount of twisting may approximate the twisting if 35 the rings were omitted, such twisting is distributed throughout the rod from ring to ring. Other advantages incident to the construction will be readily apparent to those skilled in the art. 40

What I claim is:

A tubular rotary well boring rod provided in the interior thereof at intervals intermediate its ends with one or more stiffening portions adapted to distribute torsional stresses. 45
